UNITED STATES PATENT OFFICE.

DOUGLAS KINZER AND ALDEN KINZER, OF OTTAWA, ILLINOIS.

ATTACHMENT FOR STALK-CUTTERS.

1,377,417.

Specification of Letters Patent.

Patented May 10, 1921.

Application filed August 31, 1920. Serial No. 407,201.

To all whom it may concern:

Be it known that we, DOUGLAS KINZER and ALDEN KINZER, citizens of the United States, residing at Ottawa, in the county of La Salle and State of Illinois, have invented certain new and useful Improvements in an Attachment for Stalk-Cutters, of which the following is a specification.

The present invention is designed as an improvement in seat supports for stalk cutters and has for an object the provision of a yielding support which will absorb shock occasioned by movement of the spring tension rotary knives and unevenness in the road of travel.

Another object of the invention is to provide a device of this character which is applicable to standard types of stalk cutters and may be associated therewith without making any material change in the cutter.

The above and other objects of this invention will be in part described and in part understood from the following description of the present preferred form of the invention taken in connection with the accompanying drawings wherein:

Figure 1 is an elevational view of a seat supporting structure made in accordance with my invention, a portion thereof being shown in vertical section and the seat *per se* being shown fragmentarily.

Fig. 2, is a cross sectional view taken on the line 2-2 of Fig. 1 and looking in the direction of the arrow,

Fig. 3, is a similar view taken on the line 3-3 of Fig. 1 and looking in the direction of the arrow, and

Fig. 4, is a fragmentary vertical sectional view.

In the drawings a caster wheel 4 is provided which is mounted in a fork frame 5. As is shown in Fig. 1, an axle 6 extends across said fork and is connected thereto, the wheel 4 being rotatably mounted upon the axle in the usual way.

Upstanding from the frame 5 is the seat supporting post 7 preferably of a cylindrical configuration having one end 8 thereof reduced for engagement through a corresponding opening in the apex of the frame 5 and secured from displacement by a cotter pin 9. A pair of abutment lugs 10 are formed on the outer periphery of the post 7 and are adapted for engagement with a stop 11, which is formed upon the upper end of the frame 5. In this way the phase of

movement of the post 7 will be limited to slightly less than a quarter of a circle in each direction.

An integral frame 12 consisting of a strap of metal is mounted on the post and has its ends bent downwardly and secured to permanent part 13 of the stalk cutter. It is understood that the post 7 is to be stationarily held in the frame 12 and in order to augment this a second brace 14 is provided. At the point of the post 7 with which the brace 14 contacts a portion of said post is removal to provide a flat side 15, the said brace being provided with a corresponding opening. In this way vertical movement through the frame 12 and brace 14 will be permitted, although, as is obvious, rotary movement of said post independent of said frame and brace will be prevented.

An annulus 17 is formed on the outer periphery of said post directly above the upper terminal of the flat side 15 of said post and remote from the upper terminal of the latter.

Convoluted on the upper end of said post, above the annulus 17, but in contact therewith, is a coil spring 18, the upper end of which extends beyond the upper end of the post 7. A ferrule 19 is arranged over the upper end of said spring and has its lower end terminated at a point appreciably below the upper end of the post. The ferrule consists of a metal sleeve, the upper end of which is provided with vertical incisions thereby producing segments which are bent inwardly in overlapping relation to provide a closed upper end 20.

A seat 21 of any desired shape, size or material is bolted to the closed upper end of said ferrule 19 by a bolt 22 or other desired securing means. This bolt also holds the segments of the ferrule together.

This seat supporting structure is adapted to supplant the seats now used on standard types of stalk cutters, and may be conveniently attached thereto without making material changes over this invention as herein described. The device of this invention is adapted to be placed behind the stub tongue to which the types of seats now used are secured. After being attached this device will be approximately midway between the rear of the stub tongue and the axle of the rotary knives of the stalk cutter.

What is claimed is:

1. A seat support for stalk cutters includ-

ing a post, means engaging said post with a permanent part of the cutter frame and permitting vertical but not rotatable movement of the post, and a spring pressed seat mounted upon the post.

2. A seat support for stalk cutters including a frame having a wheel mounted therein, a stop mounted upon said frame, a supporting post upstanding from said frame and rotatably connected thereto, abutment lugs carried by said post and engageable with said stop to limit the rotary movement of the post in said wheel frame, means

connecting the post with a permanent part of the cutter frame, a spring convoluted on 15 the upper end of the post and extending upwardly therebeyond, and a seat supporting ferrule mounted upon said spring.

In testimony whereof we affix our signatures in presence of two witnesses.

DOUGLAS KINZER.
ALDEN KINZER.
